VICTOR SORREL AND LOUIS ANDRÉ LAFONT, OF GRENOBLE, FRANCE, ASSIGNORS TO
UGINE-INFRA, OF GRENOBLE, FRANCE

ELECTRIC FURNACE

Application filed August 4, 1928, Serial No. 297,474, and in France September 29, 1927.

Our invention relates to electric furnaces of the resistance type suitable for thermic treatment of metals and other substances and the objects of the invention are; first, to 5 provide a device of the character described with improved means for detecting variations in temperature and for automatically regulating the temperature at the value to which the members to be treated must be subjected; second, to provide improved means 10 for assuring protection of the heating resistances by automatic diminution of the intensity of the current flowing through them when the desired temperature has been attained; and, third, to provide a furnace in 15 which the consumption of electric energy is very small, and which, moreover, is characterized by a notable equality in temperature in all parts of the furnace and an unlimited mechanical resistance to shocks to which 20 the heating body may become subjected, such as the falling of heavy metallic pieces thereon.

Briefly outlined our furnace comprises essentially a metallic heating chamber, heated 25 by means of electrical resistances and preferably protected by suitable insulation, in combination with a temperature change detecting arrangement and an automatic temperature 30 regulator consisting of a balance whose equilibrium is controlled by variations (as a function of the temperature) in magnetism of a magnetic body suspended on the said balance and extending into the interior of 35 the heating chamber, the said magnetic body being subjected to the attraction of an electro-magnet or other magnetic field produced by suitable means.

The beam of the balance is provided with 40 a suitable device for regulating the quantity of electrical energy drawn by the resistances of the furnace supplying heat thereto.

The equilibrium of the balance having been 45 destroyed by reason of the magnetic attraction developed in the magnetic body, as soon as this attraction ceases in view of the temperature of the magnetic body having attained a value where strong magnetism dis- 50 appears (Curie point), the balance regains

its equilibrium and passes from a position corresponding to a certain regulation of electrical energy (maximum heating point for example) to a position corresponding to another regulation (minimum heating point for 55 example).

If, at this second position of the balance, the temperature of the furnace tends to descend below the temperature corresponding to the critical transformation point of the magnetic body, the strong magnetism thereof becomes reestablished, the equilibrium of the balance is broken anew and hence the mean temperature of the furnace remains substantially constant and equal to the said 60 transformation point. Otherwise, the strong magnetism of the magnetic body can no longer reestablish itself and the temperature of the furnace continues to rise slowly.

The invention will now be described more 65 in detail with reference to the accompanying drawing forming part of this specification and in which—

Fig. 1 is an axial section through the furnace;

Fig. 2 is a corresponding plan view with parts removed; and

Fig. 3 is an electrical detail of the furnace partly in section.

Referring to the drawing, the apparatus 80 comprises a vertical metallic cylinder *b* having a circular, elliptical or other shape base according to the shape of the objects to be treated said cylinder being closed at its lower extremity by a bottom *b'* of the same 85 metal.

In accordance with the range of temperatures to be attained said cylinder is composed of a slightly magnetic metal or one in which strong magnetism disappears at a temperature well below the operating temperature of the furnace, which is practically inoxidizable under the conditions in which it is used and which exercises no chemical action 90 on the objects to be treated. Thus according to the scale of temperatures to be attained we use, for example, different copper bronzes or aluminum, German silver, nickel, ferro-nickel, nickel, chrome-nickel or their equivalents, whereas for the higher 95 100

temperatures or special chemical treatment, the precious metals, such as silver, gold, platinum, tungsten and their equivalents.

On the outer wall of said cylinder is spirally wound a resistance wire *c* which receives an electric current and constitutes the heating element. The insulation of the heating wire from the metallic wall may be brought about by any of the well-known means in the art such as by means of beads of refractory material threaded jointly end for end over the entire length of the wire.

At the lower extremity of cylinder *b*, beneath the bottom thereof, is disposed a powerful electro-magnet *d* which, may be of any of the well-known types in the art such as, horseshoe, bipolar, multipolar, or circular of the iron-clad type and is adapted to be excited by either direct or alternating current.

The whole is enclosed in a sheet metal casing *e* and the space between said cylinder *b* and said casing is filled with a suitable heat insulating substance *f*.

The upper extremity of the furnace is closed by means of a cover *g* of refractory material divided into two equal sectors suitably hinged at *h*—*h* and balanced to open in the direction of the arrows of Fig. 1. Said cover fits in a ring *i*, also of refractory material for assuring the closing of the annular space containing the heat insulating substance.

On the upper part of the casing *e* exterior thereto is fitted a vertical supporting tube *j* in which is held a rigid rod *k* supporting a balance *l* on its upper extremity. One end of the balance arm carries a wire rod of metal *m* penetrating the furnace through a small orifice provided for that purpose furnished in the center of the cover *g*. Within the furnace suspended on the said wire rod is a magnetic body *m'* and the balance is placed in equilibrium with the furnace out of circuit.

The balance arm supporting the wire *m* carries a contact at *n*, controlling directly or through the medium of a relay the magnitude of the current circulating in the heating element *c*.

Fig. 3 shows diagrammatically a control arrangement for direct opening and closing of the electric circuit which is particularly simple and dependable. In said figure, the contact *n* is constituted by a sort of fork 1, mounted on the balance arm by means of an insulating support 2 and the branches of which are each adapted to be plunged in a cup 3 partially filled with mercury 4 and connected in series, for example, with the circuit to be opened and closed.

Variation in electric energy supplied to the heating element *c* may be brought about by any of the well-known means in the art such as connecting in series or parallel different sections of the heating coil, coupling

the sections by threes connected in star or delta, when three-phase current is used; more generally, by varying the effective difference in potential at the terminals of the heating resistance by utilizing a rheostat, a transformer, a high and low voltage limiting relay, an induction regulator or other means known to the art.

Preferably the heat control device is arranged in such a manner that maximum heating is attained in the furnace when the beam of the balance is inclined toward the bottom of the furnace (attraction of the magnetic body *m'* by the electro-magnet *d*) and minimum heating at the moment the beam returns to its position of equilibrium (strong magnetism of body *m'* disappears).

The operation of the arrangement is as follows:

The balance *l*, which term as used in this specification is intended to include any apparatus for obtaining the value of the vertical component and capable of gravity and magnetic attraction by the mass of the magnetic body *m'* suspended from the balance beam such as a steelyard, spring and lever combinations and their equivalents, being equilibrated beforehand with the magnetic body *m'* which it supports, if the electro-magnet *d* is excited, the magnetic attraction developed by the body *m'* destroys the equilibrium and the balance beam inclines toward the bottom, placing the furnace at a working temperature of maximum heating. This attraction is observed whether the electro-magnet is fed by alternating current or direct current.

The heating coil *c* being connected to the terminals of a source of direct or alternating electric current of the desired frequency, the temperature of the furnace gradually rises and when the critical temperature at which strong magnetism disappears (Curie point) is reached in the mass of the magnetic member *m'*, the strong magnetism thereof disappears and the beam of the balance again rises to its position of equilibrium placing the furnace at a working temperature of minimum heating.

The disposition and arrangement of the parts permits obtaining, by varying the nature of the magnetic body or alloy suspended on the beam of the balance (such as nickel, iron, steel, cobalt and the like), automatically either a constant temperature in the furnace equal to the transformation temperature strength of magnetism of the magnetic body *m'* utilized or a temperature of the circuit of the furnace, increasing very slowly from the critical point of transformation of the said magnetic body *m'*.

In the first case, the value of minimum heating of the furnace is calculated and established during construction or adjusted when setting up, in such wise that in this region the

temperature tends to decrease below that corresponding to the critical point of transformation. Strong magnetism is then re-established, the equilibrium of the balance is broken anew and brings the furnace back to the high working temperature desired.

In the second case, the intensity of minimum heating is adjusted in such wise that the equilibrating temperature of the furnace subjected to this region will be slightly higher than the critical temperature of transformation of the magnetic body m' connected to the balance. Strong magnetism in said body can no longer be reestablished therefore and the temperature of the furnace continues to rise slowly.

The device and its method of operation above described are particularly suitable for attaining rapid and dependable tempering of steels. In such a case it is merely necessary to suspend the pieces to be treated from the balance beam and equilibrate the masses thereof in such a manner that the beam normally comes back to a horizontal position. The electro-magnet d being then excited, the balance beam becomes inclined and automatically establishes heating in the furnace in the neighborhood of maximum. When the transformation temperature of the heated pieces is attained (critical temperature where strong magnetism disappears) the balance returns to its position of equilibrium, thus reestablishing mild heating, minimum heating being provided, as hereinbefore described in connection with the second case, in such wise that the temperature of the furnace continues to rise very slowly. The tempering of the members in question will of course take place at different temperatures according to the composition of the steels in question, but always in the neighborhood and above the temperature of the critical point thereof. Once this point is obtained it is sufficient from then on, to follow the indications given by a thermo-couple placed in the immediate neighborhood of the pieces being treated, for determining the precise instant at which it would be suitable to effect the tempering operation.

Our process is also perfectly adapted to metallurgical operations for annealing metals or alloys. Such metals or alloys are placed in the furnace and a magnetic core whose critical point corresponds to a temperature in the neighborhood of the annealing temperature is suspended from the balance beam. Such an arrangement being established, the transformation temperature, with maximum heating is certain not to be passed. Observation of a galvanometer fed by a thermo-couple will enable the operator to stop the annealing operation at the desired temperature.

Having described our invention what we

claim as new and desire to secure by Letters Patent is—

1. An electric furnace of the type described comprising, in combination, a heat insulated metallic chamber composed of a metal which is non-magnetic at the working temperature of said furnace, an electrical resistance for heating said chamber, means for controlling the electrical energy supplied to said electrical resistance and electro-magnetic heat responsive means adapted to automatically operate said first means for regulating the temperature of said furnace. 70

2. An electric furnace of the type described comprising, in combination, a heat insulated metallic chamber, an electrical resistance for heating said chamber, a balance on said furnace, a rod suspended on one arm of said balance extending into said heating chamber, a magnetic body on the extremity of said rod, 80 means for creating a magnetic field for said body and a switch for said electrical resistance adapted to be opened and closed by the oscillations of said balance whereby the temperature of said furnace is automatically regulated. 85

3. An electric furnace of the type described comprising, in combination, a heat insulated metallic chamber, an electrical resistance for heating said chamber, a balance on said furnace, a rod suspended on one arm of said balance extending into said heating chamber, a magnetic body on the extremity of said rod, means for creating a magnetic field for said body said means including an electro-magnet 95 and a switch for said electrical resistance adapted to be opened and closed by the oscillations of said balance whereby the temperature of said furnace is automatically regulated. 100

4. An electric furnace of the type described comprising, in combination, a heat insulated metallic cylinder composed of metal which is non-magnetic at the working temperature of said furnace, a coil of resistance wire 110 wound on said cylinder, means for controlling the electrical energy supplied to said resistance coil and electro-magnetic heat responsive means adapted to automatically operate said first means for regulating the temperature of said furnace. 115

5. An electric furnace of the type described comprising, in combination, a heat insulated metallic cylinder, a coil of resistance wire wound on said cylinder, a balance on said furnace, a rod suspended on one arm of said balance extending into said heating chamber, a magnetic body on the extremity of said rod, means for creating a magnetic field for said body and a switch for said resistance coil 120 adapted to be opened and closed by the oscillations of said balance whereby the temperature of said furnace is automatically regulated. 125

6. An electric furnace comprising in com- 130

bination a heat insulated metallic cylinder composed of metal which is non-magnetic at the working temperature of said furnace, a resistance heating coil surrounding said cylinder, a magnetic body suspended within said cylinder from a movable support outside said furnace, means for creating an electro-magnetic field for said body, and a switch controlling the supply of current to said heating coil and itself controlled by the movement of said movable support.

In testimony whereof we have affixed our signatures.
